MULTIPLE SWITCH

Lee L. Manley, Philadelphia, Pa., assignor, by
mesne assignments, to Hugh H. Eby, Inc.,
Philadelphia, Pa., a corporation of Pennsyl-
vania

Application March 8, 1935, Serial No. 9,995

2 Claims. (Cl. 200—7)

This invention relates to multiple switches and particularly to devices for controlling a plurality of possibly independent circuits in predetermined synchronism.

It is among the objects of the invention; to provide a multiple switch arranged to cut on or off a power supply and simultaneously to control other circuits; to provide a multiple circuit switch arranged to effect a plurality of selected circuits under a predetermined make or break power switch condition; to improve switches generally; to provide a multiple switch arranged for increase in the number of selected circuits if desired; to provide a selector switch and a power switch mechanically interlocked so that the power control may be effective during any part of the selector switch movement; to provide means to control in a predetermined manner the make and break of a power supply and simultaneously to control other circuits which may be only indirectly coupled to the power line, as through vacuum tubes for instance; to provide means for effecting a selection of a plurality of circuits under a predeterminedly controlled power line condition; to provide a combination of a selector or wave band switch and a power switch mechanically connected and interlocked so that positive control of the power switch may be fixed during any part of the motion of the circuit selector; to provide a combined power and wave band selector switch particularly useful in radio circuits; to provide a combined selector switch with a plurality of circuits, and a power or line switch so arranged that the power may be thrown on or off at any predetermined position of the selector switch; to provide a combined power switch and selector switch which latter controls a plurality of circuits so arranged that the selector switch can be moved through a cycle of continuously progressing selector switch actions despite the actuation of the power switch at any desired point in said cycle; to provide switch means to establish a given power situation during selection from several selected circuits; and many other objects and advantages as will become more apparent as the description proceeds.

In the accompanying drawing, forming part of this description:

Fig. 1 represents a top plan of a compound switch according to one illustrative form thereof.

Fig. 2 represents a horizontal section through the illustrative form of switch shown in Fig. 1, taken on line 2—2 of Fig. 3.

Fig. 3 represents a vertical section, taken on line 3—3 of Fig. 1, and

Fig. 4 represents a diagrammatic plan of the power switch.

In some respects this invention comprises an improvement on a multiple circuit switch shown in my earlier filed application, Ser. No. 751,679, to which reference may be had for details not otherwise recited here.

A common control shaft 10 is journaled in the metallic sleeve 11, which latter supports the insulating stator plate 12, made of such material as a phenolic condensation product. Stator plate 12 engages a plate 13 of a frame 39, and is engaged by a washer 14, held by spun end 15 of sleeve 11. Washer 14 may have a stop 16 to abuttingly receive a stop arm or lug, to be described, if this should be found desirable. Although but one stop 16 is shown it will be understood that there will preferably be two in arcuately spaced relation (not shown). A depending lug 17 anchors washer 14 to plate 12.

Shaft 10 has an end of reduced diameter as at 18 upon which a washer 19 is mounted having the depending lug or stop arm 20 arranged to engage the stop 16 to limit the arcuate movement of the shaft and associated parts as predeterminedly desired. Reduced end 18 of the shaft carries the rotor plate 21 held rigidly to the shaft by the washer 22 and riveted end 23 of the shaft. Rotor plate 21 is of such insulating material as may be found most desirable.

Preferably stator plate 12 is provided with lateral flattened parallel edge 24, to secure desired smallness of the unit, unless the number of circuits to be controlled should require a larger area in which case the stator plate may be round or annular. According to the disclosure of the aforesaid application, one end of the stator plate is provided with a plurality of contact elements illustratively numbered 25, 26, 27, 28, 29 and 30. Each contact, (Fig. 3) again purely illustratively, comprises a terminal end 31, a contact area or section 32 disclosed on top of the stator, and an inner clenched terminal 33. Obviously there may be as many contacts 25, 26, etc. as may be desired, and in some cases a fewer number will be initially provided, but with the apertures through which they are threaded left open for future contact insertion as may be subsequently desired. For purposes of this application it will be understood that a pair of contacts, as 25 and 26, may be in a given circuit to be selected for certain purposes and which is closed when the contactor 41, to be described, bridges across both contacts. 55

Contacts 26 and 27 as a pair may either control another circuit, when suitably bridged by a contactor, or they may lie in different circuits so that bridging across contacts 26 and 27 affects 5 no circuit. Then contacts 27 and 28 may form the next circuit when suitably bridged, and so on. The arrangement is preferably an interlocking of circuits such that movement of the bridging contactor to bridging engagement with contacts 28 10 and 26, controls a circuit, engagement with contacts 28 and 27 controls another circuit, engagement with contacts 27 and 28 controls another circuit and so on. For certain purposes additional contact elements 34, 35, 36, 37, 38 and 39 15 may be radially disposed on the opposite end of stator plate 12, preferably but not necessarily in diametrical alignment with the respective contacts 25, 26, etc. These contact elements may either be real contacts disposed in circuits, for 20 purposes of control thereof, or they may be merely dummies or abbreviated contacts cut off as shown at 40 in Fig. 3.

The rotor plate 21 carries the bridging contact element 41 as set forth in the aforesaid application, spring pressed to engage the pairs of contacts 25 and 26, etc., and arranged to wipingly engage such pairs of stationary contacts, as the rotor plate is swung on the axis of shaft 10 through torque on said shaft, as will be understood. In the usual or preferred case there will be but a single wiping contact 41 in the rotor plate on one side of the axis of shaft 10, and for this reason the rotor plate may be relatively long and narrow as by being terminated laterally in 35 parallel edges 42. It will be obvious that there might equally well be two or more of such wiping contacts, so that there would be a plurality of circuits selectively simultaneously controlled according to the oscillations of the rotor plate on 40 and with shaft 10. The wiping contact means 41 may therefore be a two-position contact wiping on and off only by movement relative to a common polar contact, as 26, or may be a multiple circuit contact arranged to progressively control 45 a plurality of successive circuits as it advances step by step through more than one step.

For several reasons it is desirable that a second resilient wiping contact 43 be disposed at the opposite end of the rotor plate from contact 41, 50 to bear upon the real or false contact elements 34, 35, etc., and to function as a wiping contact or as a balancing registering element according to whether or not the radial contacts 34, etc. control electrical circuits. Obviously the provision of the second contact equidistant from the axis of the shaft with the first contact causes balance of the spring urge axially of the shaft to prevent lateral binding or wear on the shaft 10. The second contact engaging the blind contacts 60 also gives an increased snappy indexing of the step by step action to insure the same contact resistance for each circuit.

It will be understood that there will always be at least two alternative positions for the rotor 65 relative to the stator, with the wiping contact 41 engaging selectively one pair or another pair of contacts from at least three contacts. Obviously with a larger number of fixed contacts there may be a greater number of wiping elements 41, so 70 that simultaneously two or more pairs of fixed

contacts might be bridged by the rotor carried elements 41. Obviously certain of the contact elements 25, 26, etc., may be blind and have no circuit connections if desired, according to the demands of the situation. 5

It is frequently desirable or necessary that control of a power line be synchronized with the actuation of a selected set of contacts of a plurality of circuits. The power line may or may not have any direct electrical connection with the plurality 11 of circuits simultaneously controlled and the power line control need not be so disposed necessarily as to control the power line at the beginning or ending of the switching cycle or at any given instant or point in or relative to the selection of 15 a given circuit or plurality of circuits out of a larger number. It is only essential to the broader aspects of this invention that the power line switch be actuated at some portion of the cycle of actuation of the selector switch in one direction, and be actuated in the opposite direction at some portion of the return cycle of actuation of the selector switch. 20

A power or line switch of any desired sort, such as 44, which is merely diagrammatically shown 25 in the drawings, is mounted on frame 38, a prolongation of bracket or plate element 13, and includes terminals 45, 46, and 46a to which power connectors are to be secured. The switch has an oscillatable element 48 having a pivot 47, and is provided preferably with spaced lugs or cheeks 50 and 51 having openings between the cheeks to permit the entry and exit of a rigid stud 52, carried by the rotor 21, at a convenient point predetermined with relation to wiping contact 41, according to requirements of the combined switch of this invention. It is convenient to provide stud 52 as a continuation of the shank of the wiping contact 43 arranged to register with the blind or actual secondary contacts 34, 35, etc. 40

I claim:

1. In switches, a stator having contacts, a rotor, a pin on the rotor, a wiping contact mounted on one end of the pin in position to engage stator contacts, a power switch fixed relative to the 45 stator, an actuator operatively associated with the power switch and having a portion in the path of movement of said pin in position to be abutted by the pin to actuate the power switch in predetermined relative angular positions of the rotor 50 and stator.

2. A multiple switch comprising a stator having a face, a plurality of contacts radially disposed to overlie the stator face, a rotor having a pair of faces substantially parallel with the stator face 55 and disposed with one face in confronting spaced relation thereto, a plurality of axially resilient wiping contacts in the said space, one wiping contact having a pin extending through the rotor beyond the other face thereof, a power switch mounted on and fixed relative to said stator and having a depending portion extending beyond the free end of said pin toward the said other face of said rotor in position to be engaged by said pin in the oscillations of said rotor, and means 60 for oscillating said rotor to cause predetermined selection of contacts bridged by said wiping contacts. 65
